UNITED STATES PATENT OFFICE.

CHARLES W. MILLS AND WILLIAM W. PIDDINGTON, OF LOS ANGELES,
CALIFORNIA.

ELECTRIC RAILWAY SIGNALING SYSTEM.

SPECIFICATION forming part of Letters Patent No. 746,977, dated December 15, 1903.

Application filed June 23, 1903. Serial No. 162,792. (No model.)

To all whom it may concern:

Be it known that we, CHARLES W. MILLS and WILLIAM W. PIDDINGTON, citizens of the United States, residing at Los Angeles, in the county of Los Angeles and State of California, have invented new and useful Improvements in Electric Railway Signaling Systems, of which the following is a specification.

This invention relates to an electric railway signaling system, and is in the nature of an improvement upon an invention for which we filed an application for United States Letters Patent on the 14th day of July, 1902, Serial No. 115,539. In said application we described a novel arrangement whereby as two trains approach one another in the same block or section of a single track the engineers of the respective trains are automatically notified of the approach of the other train in the same block or system. In the same application was also described means for automatically warning the engineers in charge of two different trains that were traveling in the same direction when they entered the same block or section of the track.

It is the object of the present invention to improve the apparatus shown and described in the application for patent referred to whereby means are provided for indicating when it is safe for a train to run over any particular section of the track—that is to say, for giving a visual signal to indicate to the engineer in charge of the locomotive when the track is clear and therefore when it is safe for him to run over any particular block or section of the rails.

It has for another object to provide novel means for indicating when it will be perfectly safe for a train to run from a siding onto the main track.

It has for a further object to provide automatic indicating mechanism to give warning to the engineer in charge of a train approaching a certain point on the main line when a car or train has been improperly switched from the main track onto a siding.

It also has for its object to provide certain other improvements which will be made apparent in the description hereinafter following.

To these ends the invention consists in the

features and in the construction, arrangement, and combination of parts hereinafter described, and particularly defined in the claims following the description, reference being had to the accompanying drawings, forming part of this specification, wherein—

Figure 1 is a diagrammatic view of our improved signaling system, illustrating two trains approaching one another in the same block or track-section. Fig. 2 is a similar view showing a switch or turnout. Fig. 3 is a detail sectional view illustrating the duplex conductor and the contacts carried by a locomotive for effecting electrical contact with said conductor.

In the application for patent referred to we described an arrangement of parts so organized that when two trains approached one another in the same block or track-section the engineers of the respective trains were enabled, by means of suitable signals, to determine the location of the other train, and in said application the signaling system was illustrated as being employed in connection with a steam-railway in which the signals were situated in the cabs of the locomotives and consisted in each cab of a green and red lamp. The arrangement was such that as two trains approached one another in the same block the red lamps in the cabs were simultaneously flashed, indicating to the engineer that there was danger ahead, and when one train followed another in the same block the green lamp in the foremost engine was flashed, while the red lamp in the following engine was simultaneously flashed. We also showed and described in said application for patent telephonic apparatus which was adapted to be put into circuit and by means of which the engineer on one train could communicate with the engineer on the other train, so as to instruct him to take a siding or to transmit to him other communications or orders. In said invention we employed the rails of the railway to form a part of the conducting system and also a duplex conductor, which was coextensive with the rails and for the sake of convenience was arranged midway between the same, and in connection therewith contact members carried by the lo-

65

comotive-cab and consisting of contact-wheels which were in constant electrical contact with the duplex conductor.

All the parts referred to we employ in the present invention, and in addition thereto we also employ the novel features which will hereinafter be described.

Referring to Fig. 1 of the drawings, the numerals 1 and 2 indicate, respectively, the track-rails. One of the rails of the track is divided up at suitable points into sections separated from one another by suitable insulations 3, the rails of the tracks constituting a part of the conductors for carrying the currents to operate the signals in the cabs of the locomotives traveling on the track. Forming a part of the circuit which includes the rails 1 and 2 is a duplex conductor, (denoted in a general way by the numeral 4,) which is preferably arranged midway between the track-rails and comprises a wooden stringer 5, having secured to its upper opposite edges two parallel metallic strips 6 and 7, which form electrical conductors, said strips being separated and insulated at suitable points, as indicated at 8 in Fig. 1 of the drawings.

On the bottom of the cab of each locomotive are arranged two contacts 9 and 10, consisting of wheels that are arranged to have respectively a rolling contact with the metallic strips 6 and 7 and are fixed on a metallic shaft 11, which is journaled in yielding bearings 12, movably mounted in pendent hangers 13, suspended from the bottom of the cab. The said contact-wheels are arranged to engage at all times the contact-strips 6 and 7 of the duplex conductor. The adjacent ends of the conductor-strips 6 and 7 at the points where they are separated are connected together by resistances 14 and 15, and one of the rails of the track-section—such as 1, for example—in each section or block is connected by a crossover-wire 16 to one of the conductor-strips, such as 7, and the same rail of the adjacent track-section is connected to the conductor-strip 6 by a wire 18. This arrangement is followed out in all the different blocks or sections of the track, and the two rails of each block or section of the track are connected together by resistances 19.

The apparatus installed in each locomotive comprises three signal-lamps, respectively colored red, white, and green, a telephone, an electric bell, a battery, and a switch, arranged and connected up in a manner which we will now describe, the arrangement being shown for the sake of clearness in a diagrammatic manner. Inasmuch as the arrangement in the several different locomotives is the same, it will only be necessary to describe one of them.

Referring to Fig. 1 of the drawings, the letters A, B, and C indicate, respectively, the red, white, and green lamps which are included in a local circuit which also includes a battery 20, said circuit consisting of a wire 21, which leads from the positive side of the

battery to one blade 22 of a switch 23 and from a contact 24, which is adapted to be engaged by said switch-blade, leads a wire 25, 70 which is connected to a lever 26, which is pivoted at one end and forms the armature of an electromagnet 27. Said lever is adapted to make electrical contact with a contact 29, from which leads a wire 30 to the white lamp B, and from said white lamp leads a wire 31, which connects with a common return-wire 32, that is connected by a wire 33 to the negative side of the battery.

To the lever 26 is connected a spring 34, 80 which is constructed or adjusted to have a tension which will be coextensive with a current passing through either one of the resistances 14 or 15 and through the electromagnet, as will hereinafter be more fully explained, so 85 that said spring and current will counterbalance one another in such a manner as to hold the end of the armature-lever 26 in engagement with the contact 29.

Leading from the electromagnet to a battery 90 35 is a wire 36, and leading from said battery is a wire 37, that connects with the wheels of the locomotive-truck, and leading from the contact-wheel 9, carried by the locomotive, is a wire 38, which connects with the blade 39 95 of the switch before referred to, and leading from a contact 40, adapted to be engaged by said switch-blade, is a wire 41, that returns to the magnet 27.

The red lamp A is included in a circuit one 100 side of which is formed by the wire 32, before referred to, and the other side of which comprises a wire 42, which leads to a contact 43, that is arranged adjacent to another contact 44, from which leads a wire 45, said wire 105 being connected to an electric bell 46, from which latter leads a wire 47 back to the battery 20. The wire 45 is connected to a contact 48, which is disposed adjacent to a contact 49, and from the contact 49 leads a wire 110 50, which passes to the green light C, and said green light is connected to the battery by the return-wire 32, before referred to.

The contact-blades 22 and 39 of the switch when the latter is reversed are adapted to effect electrical engagement with two contacts 51 and 52, the contact 51 being connected by a wire 53 with the contact-wheel 10, which is in engagement with the strip 6 of the duplex conductor, and the other contact, 52, is connected by a wire 54 with a telephone 55, and from said telephone a return-wire 56 leads to the wire 47 to the negative side of the battery 20. As clearly shown in Fig. 1 of the drawings, the contacts 43 44 and 48 49 are so disposed that as the armature-lever 26 is oscillated either to the right or left each pair of said contacts will be electrically connected by said lever for a purpose which will presently be made apparent.

As before stated, the arrangement immediately above described is duplicated in the cab of each locomotive of the system, and should two of the locomotives enter the same

block the operation will be as follows: Starting from the positive side of the battery 35, the current flows from said battery by means of the wire 37 to the wheel 57 of the locomotive-truck, to the track-rail 2, to the wheel 58 of the other locomotive, through the trucks of the latter to the wheel 58^a, thence to track-rail 1 over the crossover-wire 16, to the rail 7, from the latter to the contact-wheel 9, thence 10 by wire 38 through the blade 39 of the switch 23, from the latter by the wire 41 to the magnet 27, and from the latter by the wire 36 to the battery 35, thus completing the circuit. The magnet will thus be energized and will 15 attract the armature-lever 26, and said lever will be thrown into engagement with the contacts 43 and 44, thus closing the local circuit through the red lamp, which may be traced as follows: Starting from the battery 20, the 20 current flows over the wire 21 to the blade 22 of the switch 23 and from the latter by the wire 25 to the armature-lever 26, thence over the contacts 44 and 43 to the wire 42, to the red lamp A, and from the latter back to the battery by the wires 32 and 33. The red lamp will 25 thus be thrown into action, notifying the engineer that another train is approaching him in the same block, and simultaneously with the flashing of the red light the bell 46 will be 30 sounded, giving him audible notice, as follows: A portion of the current that passes to the red lamp will pass by means of the wire 45 to the bell 46 and from the latter by means of the return-wire 47 to the battery 20. The 35 engineer will thus be given both audible and visual warning of the fact that another train is approaching him in the same track-section. The same result will occur in the cab of the other locomotive, and when the engineers receive such signals they will reverse 40 their switches 23, throwing the blades 22 and 39 into engagement with the contacts 51 and 52. They can then communicate with each other over a circuit which is traced as follows: Starting from the battery 20, the current 45 flows over the wire 21 to the blade 22 of the switch and from the latter to the contact 51 and then over the wire 53 to the contact-wheel 10 through the contact-rail 6 to and 50 over the resistance 15 to the corresponding contact-rail 6^a, thence to the contact-wheel 10^a and by the wire 53^a to the blade 39^a of the switch 23^a on the other locomotive, thence to the contact 52^a and from the latter 55 by the wire 54^a to the telephone 55^a. From the latter the current flows by the wire 56^a through the battery 20^a and from the latter by wire 21^a to the switch-blade 22^a, which is in engagement with the contact 51^a, and 60 from the latter by the wire 41^a to the contact-wheel 9^a over the contact-rail 7 and resistance 14 to the contact-wheel 9, thence by the wire 38 to the switch-blade 39, to the contact 52, and finally by the wire 54 to the telephone 55, and from the latter back to the battery 20 over the wire 47, thus completing

the telephonic circuit and enabling the engineers of the respective locomotives to communicate with each other.

As before described, the resistances are of such strength and the spring 34, which controls the armature-lever, is placed under such tension that normally the current and said spring will counterbalance each other in such a manner that the armature-lever will be held 70 in a central position—that is to say, in such a position that its end will rest in engagement with the contact 29, and when a train enters a block, there being no other train in the same block, the white lamp will be thrown 75 into action, indicating "safety," the current under such conditions being traced as follows: Starting from the battery 35 the current will flow by means of the wire 37 to the locomotive-wheel 57, thence over the rail 2 to the 80 resistance 59, over the latter to the track-rail 1^a, thence by the crossover-wire 16 to the contact-rail 7, thence through the contact-wheel 9 and by the wire 38 to the switch-blade 39, and from the latter by the wire 41 85 to the electromagnet 27, and thence over the wire 36 back to the battery 35. This will close the local circuit, but, as before described, the resistance 59 is of such strength that it will just counterbalance the spring 34 90 and will hold the armature-lever 26 in engagement with the contact 29, and the local circuit can then be traced as follows: Starting from the battery 20, the current flows over the wire 21 to the switch-blade 22 and by the 95 wire 25 to the contact-lever 26, thence by contact 29 and wire 30 to the white lamp B, and from the latter by wires 31, 32, and 33 back to the battery, thus completing the circuit and lighting the white lamp and so indicating to the engineer that there is no other locomotive or train in the block.

Should one of the track-rails become broken or displaced or the apparatus get out of order in any way, the current will then be 100 broken, whereupon the spring 34 will draw the armature-lever away from in front of the magnet and draw its end into engagement with the contacts 48 and 49, which will throw the green light C into action, the current then 105 flowing as follows: Starting from the battery 20, the current passes by means of the wire 21 to the switch-blade 22, thence by the wire 25 to the armature-lever 26, thence to contact 49, and from the latter by the wire 50 to the green 110 lamp and from the latter back to the battery by the wires 32 and 33. The green lamp will then be lighted and simultaneously with the lighting of said lamp the bell will be sounded, as a portion of the current will be diverted 115 from the armature-lever 26 to the contact 48, thence by wire 45 to the bell 46, and from the latter by the wire 47 back to the battery. The engineer will thus be given both visual and 120 audible warning that it is unsafe for him to 125 proceed.

Means are also provided for indicating

when a switch has been left open, as illustrated in Fig. 2 of the drawings. Referring to said figure, the numerals 60 and 61 indicate, respectively, the switch-rails, the rail 5 60 being connected by a wire 62 to a contact 63 and the track-rail 1^a being provided with a contact 64. The track-rails 1 and 1^a are electrically connected by a bridge-wire 65. When the switch is open, the contacts 63 and 10 64 will be thrown into engagement with each other, and the open condition of the switch will be indicated in the cab of the locomotive entering the block as follows, reference being had to the right-hand side of Fig. 2 of the 15 drawings: Starting from the battery 35^a, the current flows over the wire 37^a to the wheel 58, thence by the track-rail 2 to the switch-rail 60, over the wire 62 and contacts 63 and 64 through the track-rail 1^a, thence by the 20 crossover-wire 18^a to the contact-rail 6^a to the contact-wheel 10^a and by the wire 65 to the blade 39^a of the switch 23^a, and from said blade by the wire 41^a to the electromagnet 27^a, and from the latter by the wire 36^a back 25 to the battery, thus energizing the electromagnet and attracting the armature-lever 26^a and throwing the same into engagement with the contacts 48 and 49. The local circuit will then be closed through the red lamp A', indicating "danger," as follows: Starting from the battery 20^a the current flows by wire 21^a to the blade 22^a of the switch, from the latter by the wire 28^a to the armature-lever 26^a, thence to the contact 49 and by the wire 42^a 30 to the red lamp A', and from the latter by the wires 30^a and 33^a back to the battery. Simultaneously a portion of the current will be diverted from the armature-lever 26^a to the contact 48 and will pass, by wire 45^a, through 35 the bell 46^a and from the latter by wire 47^a back to the battery. The red lamp and the bell will thus be simultaneously thrown into action and will indicate to the engineer that it is unsafe for him to proceed.

45 We also make provision for throwing the signal to "danger" in case a car is left standing on a siding in such a manner as to foul the track—that is to say, when a car has been shunted onto a sliding, but not sufficiently far to entirely clear the track, as indicated in Fig. 2 of the drawings. Referring to said figure, the numerals 66 and 67 indicate two electromagnets which are disposed opposite one another at a point alongside the 50 track opposite the siding. Arranged between the poles of the said magnets is an armature-lever 68, which is pivoted intermediate its ends, as at 69, and is provided at one end on its opposite sides with armatures 70, which are 55 disposed opposite the ends of the poles of the two magnets. The other end of the said armature-lever is in the form of an index-hand or pointer and is adapted to traverse a graduated scale 71, which will bear suitable indications to designate the conditions of the 60 track-section or block opposite which the de-

vice is located—as, for example, the opposite ends of said graduated scale will be marked "East" and "West" or "North" or "South," as the case may be, and the central portion 70 of said scale will be marked, for example, "Clear." We have shown in Fig. 2 of the drawings a pair of wheels standing on the switch or siding in such a position that the car which is supposed to be supported by said 75 wheels would project over onto the main track, and thus would interfere with a train traveling over said main track. This condition will be indicated to the engineer on an approaching train, as follows, reference being had to the left-hand side of Fig. 2 of the 80 drawings: Commencing at battery 35, the current will flow by wire 37 to the wheel 57, thence over the track-rail 2 to a wire 72, which connects said track-rail with the 85 switch-rail 60. From the rail 60 it passes over the axles 73 of the wheels on the switch to the switch-rail 61 and by the latter to the track-rail 1^a, thence over the bridge-wire 65 to the track-rail 1, thence over by the crossover-wire 90 16 to the contact-rail 7, and from the latter to the wheel 9, and thence by wire 38 to the blade 39 of the switch 23. From said blade the current passes by wire 41 to the electromagnet 27 and from the latter by wire 36 back to the battery 35. The circuit being 95 thus completed, the armature-lever 26 in the manner before described closes the local circuit and throws the red lamp into operation in the manner before described.

100 Now let it be assumed that a train is standing on the siding—such, for example, as a local train or what is known as a "work-train"—and that it is about to proceed out onto the main track. Before going ahead on the main track it is necessary for the engineer to know whether or not the main track is clear. If the main track should not be clear, it will be indicated to the engineer on the local train, as follows, (it being assumed, 105 for example, that a train has entered the block from the right-hand side of the diagram illustrated in said Fig. 2, which for the purpose of illustration will be presumed to be from the west:) A battery 74 is connected 110 on one side by a wire 75 with the track-rail 2 and on the other side is connected by a wire 76 and by branch wires 77 and 78 to the electromagnets 66 and 67, the terminal of the magnet 66 being connected by a wire 79 115 to the conductor-rail 6^a, and the terminal of the magnet 67 is in like manner connected by a wire 80 to the conductor-rail 7^b. Starting from the battery 74, the current flows by wire 75 to the track-rail 2, thence to the 120 wheel 58, through the truck of the train to the opposite track-rail, thence by wire 16 over to the conductor-rail 7^b, thence by wire 80 to the electromagnet 67, over the wires 77 and 76 back to the battery 74, thus completing 125 the circuit. The magnet 67 will thus be energized, attracting thereto the upper end 130

of the armature-lever 68, thus throwing the other or indicating end of the said lever onto the left-hand end of the graduated scale 71, which in the example illustrated is marked 5 "West," thus indicating that a train has entered that particular block from the west and that it is therefore unsafe for the local train to proceed. It will be obvious that should a train enter the block from the east the fact 10 will be indicated by the current flowing through the magnet 66 in the same manner that it is described as flowing through the magnet 67.

In the present case we have illustrated our 15 improved signaling system as employed in connection with a steam-railway, the signals being installed in the cabs of the locomotives; but it will of course be evident that the invention is not limited in this respect and that the 20 signals may be arranged in an electric car, for example.

Having thus described our invention, what we claim as new, and desire to secure by Letters Patent, is—

25 1. In an electric signaling system, a pair of rails, a duplex conductor coöperative and substantially coextensive with the rails, said conductor and one of said rails being divided into sections insulated from one another, 30 crossover-wires connected with one part of the conductor and the section-rail at each break, and connecting-wires united with the other part of the conductor and the section-rail at said breaks, in combination with vehicles each having three signals distinguishable from one another and respectively indicating danger, safety and an abnormal condition of the track or apparatus, generators electrically connected with the signals, connections between the generators and parts of the vehicles which travel in contact with said rails, and compound contact members adapted to travel with the vehicles and having sections insulated from each other and arranged 45 to engage the parts of said duplex conductor and electrically connected with said signals.

2. In an electric signaling system, a pair of rails, a duplex conductor coöperative and substantially coextensive with the rails, said conductor and one of said rails being divided into sections insulated from one another, crossover-wires connected with one part of the conductor and the section-rail at each break, and connecting-wires united with the other part 50 of the conductor and the section-rail at said breaks, in combination with vehicles each having three signals distinguishable one from another and respectively indicating danger, safety and an abnormal condition of the track 55 or apparatus, generators electrically connected with the signals, connections between the generators and parts of the vehicles which travel in contact with said rails, compound contact members adapted to travel with the 60 vehicles and having sections insulated from each other and arranged to engage the parts

of said duplex conductor and electrically connected with said signals, and resistances connecting the adjacent ends of the duplex conductor and operating to normally hold the 70 safety signal set.

3. In an electric signaling system, a pair of rails, a duplex conductor coöperative and substantially coextensive with the rails, said conductor and one of said rails being divided 75 into sections insulated from one another, the parts of the duplex conductor being insulated from each other and connected together by resistance-coils, crossover-wires connected with one part of the conductor and the section-rail at each break, connecting-wires united with the other part of the conductor and the section-rail at said breaks, in combination with vehicles having three signals distinguishable from one another and respectively indicating danger, safety and an abnormal condition 80 of the track or apparatus, generators electrically connected with the signals, connections between the generators and a part of the vehicles which travels in contact with the said rails, compound contact members adapted to travel with the vehicles and having sections insulated from each other and arranged to engage the parts of said duplex conductor and electrically connected with 85 said signals, electromagnets in circuit with the respective signals, local circuits having a signal of a different nature from the first-named signals, and armatures for said magnets constituting circuit-closers for said local 90 circuits.

4. In an electric signaling system, a pair of rails, a duplex conductor coöperative and substantially coextensive with the rails, said conductor and one of said rails being divided 105 into sections insulated from one another, and connected together by resistance-coils, the parts of the duplex conductor being insulated from each other, crossover-wires connecting one part of the duplex conductor to the section-rail at each break, connecting-wires united with the other part of the conductors and the section-rail at another break, in combination with vehicles having lamps 110 of three different colors, generators electrically connected with the lamps, connections between the generators and a part of the vehicles which travels in contact with the said rails, compound contact members adapted to travel with the vehicles and having the sections insulated from each other and arranged to engage the parts of said duplex conductor and electrically connected with said signals, electromagnets in circuit with said lamps, local circuits each having a bell, armatures for 115 said magnets constituting circuit-closers for said local circuits, and springs arranged, when the current passes through said resistances, to hold the armatures in a position to close the circuit through the lamps indicating safety.

5. In an electric signaling system, a pair of

rails, a duplex conductor coöperative and substantially coextensive with the rails, said conductor and one of said rails being divided into insulated sections, the parts of the duplex 5 conductor being insulated from each other and connected together by resistances, crossover-wires connecting one part of the conductor to the section-rail at each break, connecting-wires united with the other part of the 10 conductor and each rail at said breaks, in combination with vehicles having three visual signals distinguishable from each other and respectively indicating danger, safety and an abnormal condition of the track or 15 apparatus, generators electrically connected with said signals, connections between the generators and a part of the vehicles which travels in contact with said rails, compound contact members adapted to travel with the 20 vehicle and having sections insulated from each other, arranged to engage the parts of said duplex conductor and electrically connected with said signals, electromagnets in circuit with said signals, local circuits each 25 having audible signals, and armatures for said magnets constituting circuit-closers for said local circuits.

6. In an electric signaling system, a pair of rails, a duplex conductor arranged between 30 the rails and substantially coextensive therewith, said conductor and one of said rails being divided into sections separated from one another, the parts of the duplex conductor being insulated from each other and connected 35 together by resistance-coils, crossover-wires connecting one part of the conductor and the section-rail at each break, connecting-wires united with the other part of the conductor and the section-rail at said breaks, 40 combined with vehicles having three signals distinguishable from each other and respectively indicating danger, safety and an abnormal condition of the track or apparatus, generators electrically connected with said 45 signals, connections between the generators and the wheels of the vehicles, and compound contact members arranged to travel with the vehicles and having sections insulated from each other, arranged to engage the parts of 50 said duplex conductor and electrically connected with said signals.

7. In an electric signaling system, a pair of rails, a duplex conductor coöperative and substantially coextensive with the rails, said conductor and one of said rails being divided into sections separated from one another, the parts of the duplex conductor being insulated from each other and connected together by 55 resistance-coils, crossover-wires connecting one part of the duplex conductor and the section-rail at each break, and connecting-wires uniting the other part of the conductor and the section-rail at said breaks, in combination 60 with vehicles each carrying three signals 65 distinguishable from each other and respectively indicating danger, safety and an ab-

normal condition of the track or apparatus, telephones carried by said vehicles, electrical connections between the signals, telephones, rails and duplex conductor, each of the connections including a battery, and switches on the vehicles for closing either the signal or telephone circuits at will. 70

8. In an electric signaling system, a pair of rails, a duplex conductor coöperative and substantially coextensive with the rails, said conductor and one of said rails being divided into sections separated from one another, the parts of the duplex conductor being insulated from each other and connected together 80 by resistances, crossover-wires connecting one part of the duplex conductor and the section-rail at each break, connecting-wires uniting the other part of the conductor and the section-rail at said breaks, in combination with vehicles, three signals carried by each vehicle distinguishable from one another and respectively indicating danger, safety and an abnormal condition of the track or apparatus, means for normally placing 85 one of said signals in operation to indicate safety, and electrical connections between the signals, rails and duplex conductor. 90

9. In an electric signaling device, a pair of rails, a duplex conductor coöperative and substantially coextensive with the rails, said conductor and one of said rails being divided into sections separated from one another, the parts of the duplex conductor being insulated from each other and connected together 95 by resistance-coils, crossover-wires connecting one part of the duplex conductor and the section-rail at each break, and connecting-wires uniting the other part of the conductor and the section-rail at said breaks, a pair of 100 switch-rails, one of said switch-rails being electrically connected with one of the track-rails, means for connecting said switch-rail with the other track-rail when the switch is open, two electromagnets arranged opposite 105 one another and respectively electrically connected with the parts of the duplex conductor, a battery connected to said electromagnets and to one of the track-rails, an oscillatory 110 armature lever disposed between the poles 115 of said magnets, and a graduated index over which the free end of said armature is arranged to travel, for the purpose specified. 115

10. In an electric signaling device, a pair of rails, a duplex conductor coöperative and substantially coextensive with the rails, said conductor and one of said rails being divided into sections separated from one another, the parts of the duplex conductor being insulated from each other, crossover-wires connecting one part of the duplex conductor and the section-rail at one break, connecting-wires uniting the other part of the conductor and the section-rail at said breaks, two electromagnets arranged opposite one another, 120 two corresponding terminals of said magnets being connected to a battery which is also 125 130

electrically connected to one of the track-rails, the other terminals of said magnets being respectively connected to the parts of the duplex conductor, and an oscillating armature constituting an index-hand disposed between the poles of said electromagnets, for the purpose specified.

In testimony whereof we have hereunto set

our hands in presence of two subscribing witnesses.

CHARLES W. MILLS.

WILLIAM W. PIDDINGTON.
